COSMETIC POWDER CONTAINER AND
DISPENSER

Albert E. Vaughn, Orange, N. J.

Application January 13, 1945, Serial No. 572,591

3 Claims. (Cl. 15—131.1)

1

This invention relates to the container art and more particularly, to a container device for cosmetics, such as face powder, powdered rouge, and the like, which is adapted to contain a cosmetic and to dispense the same in desired quantities.

The present invention is an improvement on the device illustrated and described in my Patent No. 2,365,921, dated December 26, 1944, for Container for Cosmetic Powder, to which reference is hereby made.

It is a primary object of my present invention to provide a dispensing container for powder or the like, having a powder receptacle with dispensing means secured thereto and a cap to enclose the dispensing means, in which securing means are provided between the removable cap and the receptacle to permit the cap to be positively secured to the receptacle. This feature insures against accidental displacement of the cap from the receptacle, as commonly occurs in a woman's purse or handbag, to prevent powder or rouge carried by the container from being discharged and soiling adjacent articles in the purse or handbag.

A further object of the invention is to provide such a dispensing container as is generally described above, in which the powder or other cosmetic is carried in an inner receptacle insertable into an outer receptacle, with means for locking the receptacles together. This permits the inner receptacle, when empty, to be replaced by a freshly filled receptacle, which freshly filled receptacle can be sold separately at substantially lower cost than the complete device, to accommodate the user. In such construction I prefer to form the outer receptacle of an opaque material, such as, for example, glass or one of the synthetic resins, and to form the inner receptacle of a transparent material, such as, for example, glass or one of the synthetic resins, providing an opening in the outer receptacle through which the contents of the inner receptacle may be viewed by the user. This permits a prospective purchaser or user to determine by direct observation the true color of the powder or other cosmetic contained in the inner receptacle, and this construction is a further feature of the invention.

Another object of the invention is to provide such a dispensing container, as is generally described above, in which the dispensing means may be flexed by the user to provide a pumping action tending to eject powder from the container. While this may be accomplished in several ways, as pointed out hereinafter, I prefer to accomplish it by providing a resilient cushion

2

on the container, covered by a sheet of powder-permeable fabric, the cushion being inwardly flexible to provide a pumping action whereby air in the container, laden with powder, is forced outwardly through the sheet of fabric by inwardly flexing the cushion.

Still another object of the invention is to provide such dispensing container, as generally described above, in which the bottom of the powder containing receptacle is provided with a flexible portion which may be flexed by the user to assist, by a pumping action, in the ejection of powder from the receptacle. This greatly facilitates the use of the device and permits the contents of the receptacle to be readily agitated to prevent any tendency toward caking thereof due to the absorption of moisture or otherwise.

Other objects and advantages of the invention will be apparent from the following specification and the drawing, which is for the purpose of illustration only, and in which:

Fig. 1 is a vertical view, partly in section, of a preferred embodiment of my device.

Fig. 2 is a cross-sectional view taken on the line 2—2 of Fig. 1.

Fig. 3 is an exploded perspective view illustrating the construction of Fig. 1.

Fig. 4 is a vertical sectional view taken through an alternative embodiment of the invention.

Fig. 5 is a vertical view, partly in section, of a further alternative form of the invention.

Referring to Fig. 1 of the drawing, I show a powder receptacle 10 including an outer receptacle 11 and an inner receptacle 12. The outer receptacle 11 includes a tubular side wall 13 and a circular bottom wall 14, the latter having a centrally disposed opening 15 therethrough. The inner receptacle 12 is provided with a tubular inner side wall 17 and a bottom wall 18, forming a container which is closed on the bottom. The inner receptacle 12 is preferably formed of a transparent material, such as, for example, glass or a synthetic resin, so that the contents thereof may be readily visible through the walls thereof. The outer receptacle 11 is preferably formed of an opaque material, such as, for example, a synthetic resin, so that when the inner receptacle is disposed within the outer receptacle the contents of the former will be hidden by the latter, but permitting ready viewing thereof through the opening 15 in the circular bottom wall 14 of the outer receptacle 11.

Formed on the inner surface 19 of the tubular side wall 13 of the outer receptacle 11 are a plurality of threads 20 which are adapted to be en-

gaged by threads 21 formed on the outer surface of the inner side wall 17 of the inner receptacle 12. As will be apparent from Fig. 2, rotation of the inner receptacle 12 in a clockwise direction relative to the outer receptacle 11 causes the threads 21 to engage the threads 20 so as to secure the receptacles together. Relative counter-clockwise rotation of the inner receptacle 12 relative to the outer receptacle 11 readily frees the inner receptacle from the outer receptacle to permit the removal thereof therefrom. The threads 20 and 21 constitute a securing means between the inner and outer receptacles for releasably securing them together in response to relative rotation therebetween.

The outer surface of the tubular outer side wall 13 is likewise provided with threads 23 which are adapted to engage threads 24 formed on an inner surface 25 of a cap member 26. As will be apparent from Fig. 2, rotation of the cap member 26 in a clockwise direction relative to the outer receptacle 11 will cause the threads 24 to engage the threads 23 so as to secure the cap member relative to the outer receptacle, thus forming a second securing means of the invention for positively securing the cap member relative to the outer receptacle, and this is also a feature of the invention, preventing inadvertent displacement of the cap member from the outer receptacle and preventing leakage of powder therefrom.

Spanning the top of the tubular inner side wall 17 of the outer receptacle 11 is a circular supporting member 28 constituting a supporting means of the invention, which is provided with a central aperture 29 of substantial diameter, and which is further provided with an annular depending flange 30 which telescopes downwardly over the upper end of the inner side wall 17, as illustrated in Fig. 1. The circular supporting member 28 is preferably formed of metal or other material resistant to flexure.

Supported on the circular supporting member 28 is a cushion 31, preferably formed of porous rubber or other resilient material, having a central passage 32 therein which registers with the central aperture 29 of the supporting member 28, but is preferably considerably smaller in diameter. Covering the cushion 31 is a sheet of fabric 34 which serves to retain a mass of powder or other cosmetic 35 within the inner receptacle 12, but which is sufficiently pervious to the powder to permit the same to filter out of the receptacle through the sheet. The sheet of fabric 34 is preferably flexible in character and is preferably of the silken velure or other velvet-like type, the pile of the fabric being turned outward. I prefer to employ a fabric having a rayon pile, since rayon fibers are peculiar in having what may be termed a "self-cleaning" character, especially with respect to contamination by oily substances. The outer edge of the sheet of fabric 34 is doubled back under the annular depending flange 30 of the supporting member 28 between the flange and the tubular inner side wall 17 of the inner receptacle 12, the fit being sufficiently tight to retain the sheet and its contents relative to the inner receptacle.

As will be apparent from the foregoing description, the inner receptacle 12, when empty, may readily be replaced by a similar full receptacle, with the advantages therefor pointed out above. Also, it will be apparent that the cap member 26 is readily removable from the powder receptacle 10 to permit use thereof, but that the cap mem-

ber may be secured relative to the receptacle so as to insure against relative displacement therebetween.

In the alternative embodiment illustrated in Fig. 4, I provide a one-piece powder receptacle 37 having a tubular side wall 38 and a bottom wall 39 closing the lower end of the side wall to form a powder container adapted to contain a mass of powder 40. The outer surface of the tubular side wall 38 is provided with threads 41, similar to the threads 23, adapted to engage and cooperate with suitable threads formed on the inner surface of a cap member 42, similar to the cap member 26. Supported on the upper end of the tubular side wall 38 is an annular supporting member 43 having a central opening 44 therein and adapted to support a cushion 45, preferably in the form of a convex resilient disk formed of resilient material, such as, for example, rubber, which is provided with a central aperture 46 of substantially smaller diameter than the central opening 44. Covering the cushion 45 is a sheet of fabric 47, similar to the sheet of fabric 34, the outer edge of which is secured between the annular supporting member 43 and the tubular side wall 38. In this form of the invention, as will be apparent, the cushion 45 may be substantially flexed inwardly relative to the central opening 44 in the supporting member 43, to force powder from the interior of the receptacle 37 outwardly through the central aperture 46 in the cushion and through the sheet of fabric 47. By utilizing a relatively thin flexible cushion, the pumping action caused by inward flexure of the cushion is enhanced substantially, and this is an object of this alternative embodiment of the invention.

In the alternative embodiment illustrated in Fig. 5, I show a powder receptacle 50 including a tubular side wall 51 and a bottom wall 52 having a recessed opening 53 therein into which is secured, as by cementing or otherwise, a flexible disk 54, preferably formed of a relatively thin flexible material, such as, for example, Celluloid, which closes the lower end of the receptacle. Supported on the upper end of the tubular side wall 51 is an annular supporting member 56, similar to the circular supporting member 28, which supports a cushion 57, similar to the cushion 31, the same being enclosed by a sheet of fabric 58, similar to the sheet of fabric 34, and suitably retained between the supporting member and the side wall. The cushion 57 is provided with a central passage 59 of substantially smaller diameter than a central opening 60 formed in the supporting member 56, similar to the construction illustrated in Fig. 1. Although inward flexure of the cushion 57 causes a certain degree of pumping, as described above in connection with the embodiment shown in Fig. 4, the pumping effect is substantially enhanced by the flexible disk 54 which can be flexed to agitate the contents of the receptacle 50 so as to force powder therefrom outwardly through the sheet of fabric 58. As shown in Fig. 4, the construction illustrated in Fig. 5 is provided with threads 61 on the exterior of the tubular side wall 51 which are adapted to engage suitable threads formed on the interior wall of a cap member 62, to secure the cap member relative to the receptacle.

While I have shown and described a preferred embodiment of my invention, together with two alternative embodiments, it will be understood by those skilled in the art that certain elements and details of such embodiments may be replaced

by others having equivalent functions, and that I do not intend to be limited to the specific forms shown, or any of them, but desire to be afforded the full scope of the following claims.

I claim as my invention:

1. In a powder container of the character described, the combination of: a tubular powder receptacle member having a side wall, a bottom wall and an open end, said member being adapted to contain a powder, said bottom wall having a flexible portion adapted to be flexed to displace powder from said receptacle member; a supporting element supported on said side wall, said supporting element having an aperture therethrough communicating with the interior of said receptacle member; a resilient cushion supported on said supporting element and having an orifice therethrough of smaller size than said aperture communicating with said aperture; and a sheet of fabric covering said cushion and secured relative to said receptacle member and extending across the open end of said receptacle member, said fabric being pervious to the powder to permit the powder to be dispensed therethrough from said receptacle member with a pumping action when the approximate central portions of said cushion and said covering are substantially flexed inwardly relative to said aperture.

2. In a powder container of the character described, the combination of: a tubular powder receptacle member having a side wall, a bottom wall and an open end, said member being adapted to contain a powder, said bottom wall having a flexible portion adapted to be flexed to displace powder from said receptacle member through said open top; a supporting element supported on said side wall, said supporting element having an aperture therethrough communicating with the interior of said receptacle member; a resilient cushion supported on said supporting element and having an orifice therethrough of smaller size than said aperture communicating with said aperture; a sheet of fabric covering said cushion and secured relative to said receptacle member and extending across the open end thereof, said fabric being pervious to the powder to permit the powder to be dispensed therethrough from said receptacle member; and a removable cap member adapted to telescope over said side wall to enclose said sheet, the combined flexing of said bot-

tom wall and flexing of the approximate central portions of said cushion and fabric inwardly relative to said aperture effecting a pumping action for feeding powder from said receptacle member.

3. In a powder container of the character described, the combination of: a tubular powder receptacle member having a side wall, a bottom wall and an open end, said member being adapted to contain a powder, said bottom wall having a flexible portion adapted to be flexed to displace powder from said open end of said receptacle member; a supporting element supported on said side wall, said supporting element having an aperture therethrough communicating with the interior of said receptacle member; a resilient cushion supported on said supporting element and having an orifice therethrough of smaller size than said aperture communicating with said aperture; a sheet of fabric covering said cushion and secured relative to said receptacle member, said fabric overlying said open end of said receptacle member and being pervious to the powder to permit the powder to be dispensed therethrough from said receptacle member; and a removable cap member adapted to telescope over said side wall to enclose said sheet, the combined flexing of said bottom wall and flexing of the approximate central portions of said cushion and fabric inwardly relative to said aperture effecting a pumping action for feeding powder from said receptacle member.
